OTIS W. MOORE, OF ALLERTON, ILLINOIS.

DEVICE FOR HOLDING AND DISPLAYING MAPS, DIAGRAMS, &c.

1,371,510.

Specification of Letters Patent. Patented Mar. 15, 1921.

Application filed February 2, 1920. Serial No. 355,637.

To all whom it may concern:

Be it known that I, OTIS W. MOORE, a citizen of the United States, residing at Allerton, in the county of Vermilion and

5 State of Illinois, have invented certain new and useful Improvements in Devices for Holding and Displaying Maps, Diagrams, &c.; and I do hereby declare the following to be a full, clear, and exact description 10 of the invention, such as will enable others skilled in the art to which it appertains to make and use the same.

The present invention relates to a device for holding and displaying maps, diagrams, 15 etc., and aims to provide an extremely simple and convenient means for holding a map, diagram or the like, within small compass and enabling same to be displayed conveniently.

20 A further object is the provision of such a device embodying a web containing the map, diagram, or the like, wound upon two rolls, and the arrangement being such that the map or diagram can be unwound from 25 one roll and wound upon the other to bring the successive portions of the map into view, and without requiring a special mounting for the rolls or other complicated structure as usually employed for this purpose.

30 It is also the object of the invention to provide a device of the nature indicated which will serve as a protection for the map or diagram, and enabling it to be carried within small space, as well as affording convenient means for bringing the successive 35 portions of the map into view.

With the foregoing and other objects in view, which will be apparent as the description proceeds, the invention resides in 40 the construction and arrangement of parts hereinafter described and claimed, it being understood that changes can be made within the scope of what is claimed without departing from the spirit of the invention.

45 The invention is illustrated in the accompanying drawing, wherein:—

Figure 1 is a perspective view of the device, portions being broken away.

Fig. 2 is a side elevation thereof showing 50 how the hand can be used for unwinding the web from one roll, and winding it on the other.

In carrying out the invention, two rolls 1 of suitable size are employed, and they 55 can be of any suitable material. A pliant web 2 of suitable length and width is wound

in opposite directions on the rolls, and consists of a sheet 3 of fabric or other suitable non-tearing flexible material on which the map, diagram, or the like is disposed, as at 60 4. A sheet 5 of celluloid or other transparent material is disposed over the map or diagram and is coextensive in width and length with the sheet 3, so as to protect the map or diagram from being soiled in handling or otherwise marred. The ends of the web can be secured to the rolls 1 in any suitable manner, if desired.

The web 2 is wound upon the rolls until the two wound portions of the web contact 70 with one another, and one or more elastic bands 6 of rubber or other elastic material embrace the rolls and thus hold them in frictional contact as well as keeping the web wound on the rolls. These bands will hold 75 the device within small compass, and in holding the wound portions of the web in contact, will prevent the web from unwinding from either roll, thereby holding the exposed portion of the map in place. The de- 80 vice can thus be conveniently carried or stored away, and the transparent covering or sheet 5 will protect the map or diagram from being soiled or injured. By placing the rolls on a surface and placing the palm 85 of a hand on the web, and moving the hand in either direction, the web can be unwound from one roll and wound on the other, the wound portions of the web slipping past one another, and the celluloid sheet 5 fa- 90 cilitating such slippage where the wound portions contact. In this way, the successive portions of the map or diagram, which can be of any suitable length, are brought 95 into view. Thus, an observer in an automobile, airplane, train or other vehicle, can "turn" or advance the map or diagram as the vehicle progresses enabling the observer to make comparisons or observations.

The device is not only useful for holding 100 maps or diagrams of routes traveled, but can also be used for holding drawings, diagrams, blue prints and the like. A further advantage of the device resides in the fact that a number of them can be used for 105 holding sections of a large map or diagram, and the devices can be placed with the webs edge to edge and the rolls end to end, thereby setting up the map without requiring rolls of considerable length. The several 110 sets of rolls can thus be carried and stored within smaller space, and, furthermore,

each section of the map can be used separately. A cardinal feature of the invention is the absence of a casing or other mounting for the rolls, and the convenience with 5 which the map or diagram can be carried and stored and the successive portions thereof brought into view, without danger of the web unwinding accidentally.

The rolls may also be conveniently 10 grasped lightly by both hands, and by a slight rotating and reciprocal pressure, the web is easily rolled from one roll to the other.

Having thus described the invention, what 15 is claimed as new is:—

1. A device for holding and displaying maps, diagrams, etc., comprising a web having wound portions, and means embracing said wound portions for holding them 20 wound and in frictional contact with one another.

2. A device for holding and displaying maps, diagrams, etc., comprising rolls, a web wound upon said rolls, and means embracing said webs and rolls for holding the 25 web wound on the rolls and said wound portions in frictional contact.

3. A device for holding and displaying maps, diagrams, etc., comprising a web hav-

ing portions wound in opposite directions, and an elastic band embracing said web for holding said portions wound and in frictional contact with one another.

4. A device for holding and displaying maps, diagrams, etc., comprising a pair of 35 rolls, a web wound in opposite directions upon said rolls, and an elastic band embracing said web and rolls for holding the wound portions of the web on the rolls and for holding said wound portions in frictional contact.

5. A device for holding and displaying maps, diagrams, etc., comprising a pair of 45 rolls, a web having a sheet for the map, diagram or the like, and a transparent covering, said web being wound in opposite directions on the rolls, and an elastic band embracing said web and rolls for holding the web wound on the rolls and for holding said wound portions in frictional contact.

In testimony whereof I have signed my name to this specification in the presence of two subscribing witnesses.

OTIS W. MOORE.
